MISSILE PROJECTING DEVICE

Harry A. Douglas, Bronson, Mich.

Application September 26, 1934, Serial No. 745,552
Renewed July 2, 1936

16 Claims. (Cl. 273—107.5)

This invention relates to missile projecting devices, and has for an object the provision of a new and improved device of this character.

In the drawing accompanying this specification and forming a part of this application, I have shown, for purposes of illustration, one embodiment which my invention may assume, and in the drawing:

Figure 1 is a side elevational view of a missile projecting device constructed according to the invention;

Figure 2 is a fragmentary enlarged vertical sectional view of the device shown in Figure 1, disclosing the operative parts in a normal position of rest;

Figure 3 is a view similar to Figure 2, and disclosing the operative parts in position to discharge the missile;

Figure 4 is an enlarged fragmentary perspective view of one end of the bow, and showing the manner in which the bow string is attached thereto, while

Figure 5 is a fragmentary vertical sectional view of the projecting device, showing another embodiment of the invention.

As shown in the drawing, the invention comprises a missile projecting device, including a bow 6 of suitable resilient material, to the ends of which is secured a bow string 7 looped and knotted as best shown at 8 in Figure 4.

The bow 6 is perforated at a central point, as indicated at 9, and extending through the perforation 9 is a combined cylinder and barrel member, the cylinder 10 being of substantial diameter, 35 open at one end, as indicated at 11, and the opposite end 12 snugly fitted into the perforation 9 in the bow 6, the cylinder 10 being provided with an exterior annular flange 13 which abuts the inner surface of the bow 6, and being further 40 provided with an annular flange 14 closely fitting against the opposite surface of the bow 6, the latter flange being formed from an initially cylindrical projection, indicated in dotted lines in Figure 3, which is upset by a suitable operation 45 subsequent to insertion through the perforation 9, resulting in the bow 6 being firmly clamped between the flanges 13 and 14.

The cylinder 10 has a bore 15 tapered at its inner end and further reduced, as indicated at 50 16, and immediately in advance of the reduced bore 16, there is provided a rounded seat 17 for accommodation of a ball missile 18, and the rounded seat 17 merges with the cylindrical bore 19 formed in the barrel 20. The barrel 20 projects forwardly of the bow 6 a considerable dis-

tance and is preferably formed integrally with the cylinder member 10; in fact the cylinder 10 and barrel 20 may be bored from one casting resulting in a strong and accurately furnished construction. A piston 21 is reciprocably mounted 5 in the bore 15 of the cylinder 10 and is provided with a rod 22 having a perforation 23 in its end through which the bow string 7 freely passes.

In Figure 5 there is shown a slightly different embodiment of the missile projecting device; in this embodiment the bow 25, cylinder 26, flanges 27 and 28, barrel 29 and piston 30 correspond to the parts 6, 10, 13, 14, 20, and 21 heretofore referred to, and a bow string, not shown, similar to the bow string 7 is also used. The interior construction of the cylinder 26 and barrel 29 differs, however, in order to accommodate a different type of missile, such as a dart 31, the bore 32 of the barrel 29 being of a size to snugly accommodate 15 the shaft of the dart 31, and the passage 33 is 20 made smaller than the diameter of the dart shaft, and communicates with the bore of the cylinder 26 in the same manner as before described.

In operation a ball 18 is inserted into the bore 19 of the barrel 20 so as to rest against the seat 25 17, the bow 6 being then grasped and supported by one hand of the user, and the string 7 pulled back to bend the bow 6 and retract the piston 21; when the string 7 is released air is compressed 30 within the cylinder 10, and ejects the ball 18 from the barrel 20. The construction shown in Figure 5 operates in a similar manner.

It will be appreciated that the device is manipulable exactly in the manner of an ordinary bow, yet is more powerful and accurate in its shooting qualities than the ordinary bow and arrow, and by reason of its construction is ideally suitable for use as a toy, though equally suitable in large size as an effective weapon.

Under these circumstances it will be apparent 40 to those skilled in the art that I have accomplished at least the principal object of my invention. On the other hand, it also will be apparent to those skilled in the art that the disclosure herein is illustrative only, and may be variously and extensively modified, while still retaining 45 part or all of the advantages of my invention, and without departing from my invention, and that my invention in no sense is limited to this or any specific embodiment or disclosure.

I claim:

1. A bow means operated pneumatic missile-projector, comprising: air compressor means; missile accommodating means; and bow means, including a bow and a bow string, connected to

said compressor means to effect operation of said compressor means by said bow means upon return of said bow means from tensioned position; said projector having a passage forcing air compressed by said compressor means into said missile accommodating means to project a missile positioned thereon.

5 2. A bow means operated pneumatic missile-projector, comprising: bow means, including a bow and a bow string; air compressor means; and missile accommodating means; said projector having a passage for conducting the compressed air into said missile accommodating means to project a missile therefrom; and said bow string and said bow cooperating to operate said compressor means when said bow means are released.

10 3. A bow means actuated pneumatic missile-projector, comprising: bow means, including a bow and a bow string operatively connected; air compressor means, functionally interposed between said bow string and said bow whereby said bow means when released from tensioned position operates said air compressor means; and supporting means, for supporting a missile in position to be projected; said projector having a passage leading from said air compressor means to in rear of a missile so supported, whereby operation of said air compressor means by said bow means delivers compressed air in rear of said 15 missile to project said missile.

20 4. A bow means actuated pneumatic missile-projector, comprising: bow means, including a bow and a bow string operatively connected; air compressor means carried by said bow, and connected to said bow string, whereby said bow means when released from tensioned position operates said air compressor means; and supporting means, for supporting a missile in position to be projected; said projector having a 25 passage leading from said air compressor means to in rear of a missile so supported, whereby operation of said air compressor means by said bow means delivers compressed air in rear of said missile to project said missile.

30 45 5. A bow means actuated pneumatic missile-projector, comprising: bow means, including a bow and a bow string operatively connected; air compressor means, including a cylinder means, and a piston means operable in said cylinder means, one of said means being connected to said bow, and the other of said means being connected to said bow string, whereby said bow means when released from tensioned position moves said piston means with respect to said cylinder means to compress air within said cylinder means; and supporting means, for supporting a missile in position to be projected; said projector having a passage leading from said cylinder means to in rear of a missile so supported, whereby operation of said piston means by said bow means delivers compressed air in rear of said missile to project said missile.

55 6. A bow means actuated pneumatic missile-projector, comprising: bow means, including a bow and a bow string operatively connected; air compressor means, including a cylinder, and a piston operable in said cylinder, said cylinder being connected to said bow, and said piston being connected to said bow string, whereby said bow 60 means when released from tensioned position moves said piston with respect to said cylinder to compress air within said cylinder; and supporting means, for supporting a missile in position to be projected; said projector having a passage leading from said cylinder to in rear of a 65 missile.

7. A bow means actuated pneumatic missile-projector, comprising: bow means, including a bow and a bow string operatively connected; air compressor means, including a cylinder, and a piston operable in said cylinder, said cylinder being connected to said bow, and said piston having a self-adjusting relatively movable connection with said bow string, whereby said bow means when released from tensioned position moves said piston with respect to said cylinder to compress air within said cylinder; and supporting means, for supporting a missile in position to be projected; said projector having a passage leading from said cylinder to in rear of a missile so supported, whereby operation of said piston by said bow means delivers compressed air in rear of said missile to project said missile.

8. A bow means actuated pneumatic missile-projector, comprising: bow means, including a bow and a bow string operatively connected; air compressor means, including a cylinder, and a piston freely insertable and withdrawable with respect to said cylinder, said cylinder being connected to said bow, and said piston having a connection with said bow string, whereby said bow means when released from tensioned position moves said piston with respect to said cylinder to compress air within said cylinder; and supporting means, for supporting a missile in position to be projected; said projector having a passage leading from said cylinder to in rear of a missile so supported, whereby operation of said piston by said bow means delivers compressed air in rear of said missile to project said missile.

9. A bow means actuated pneumatic missile-projector, comprising: bow means, including a bow and a bow string operatively connected; air compressor means, including a cylinder, and a piston freely insertable and withdrawable with respect to said cylinder, said cylinder being connected to said bow, and said piston having a self-adjusting relatively movable connection with said bow string, whereby said bow means when released from tensioned position moves said piston with respect to said cylinder to compress air within said cylinder, the said connection of said bow string with said piston serving to maintain said piston assembled with said cylinder; and supporting means, for supporting a missile in position to be projected; said projector having a passage leading from said cylinder to in rear of a missile so supported, whereby operation of said piston by said bow means delivers compressed air in rear of said missile to project said missile.

10. A bow means actuated pneumatic missile-projector, comprising: bow means, including a bow and a bow string; air compressor means; missile accommodating means; said projector having a passage for conducting the compressed air into said missile accommodating means to project a missile therefrom; said bow string and said bow cooperating to operate said compressor means when said bow means are released; and a barrel carried by said projector, having a bore communicable with said missile accommodating means, and operable to exert a directional influence upon a missile issuing therefrom.

11. A bow means operated pneumatic missile-projector, comprising: bow means, including a

bow and a bow string; air compressor means; missile accommodating means; said projector having a passage for conducting the compressed air into said missile accommodating means to project a missile therefrom; said bow string and said bow cooperating to operate said compressor means when said bow means are released; and a barrel carried by said projector, projecting in advance of said bow, having a bore communicable with said missile accommodating means, operable to exert a directional influence upon a missile issuing therefrom, and providing an extension which may be aimed in the manner of a gun barrel.

12. A bow means operated pneumatic missile-projector, comprising: bow means, including a bow and a bow string; air compressor means, including a cylinder, and a piston operable to compress air in said cylinder; missile accommodating means; said projector having a passage for conducting the compressed air from said cylinder into said missile accommodating means to project a missile therefrom; said bow string and said bow cooperating to operate said compressor means when said bow means are released; and a barrel, having a bore communicable with said missile accommodating means, and operable to exert a directional influence upon a missile issuing therefrom, said barrel and said cylinder being of integral formation.

13. A bow means operated pneumatic missile-projector, comprising: bow means, including a bow and a bow string; air compressor means including a cylinder and piston; missile accommodating means; said projector having a passage for conducting the compressed air into said missile accommodating means to project a missile therefrom; said bow string and said bow cooperating to operate said compressor means when said bow means are released; and a barrel, having a bore communicable with said missile accommodating means, said cylinder and said barrel comprising a single integral fitting having spaced bores connected by a constricted passage cooperating to define said missile accommodating means.

14. A bow means operated pneumatic missile-projector, comprising: bow means, including a bow and a bow string, said bow having a central perforation; a tubular fitting including the cylinder of air compressor means; missile accommodating means, having a passage for conducting

the compressed air into said missile accommodating means to project a missile therefrom; and said bow string and said bow cooperating to operate said compressor means when said bow means are released; said fitting extending through the perforation in said bow, and having spaced abutment means fitting against opposite sides of said bow, one of said abutments means comprising a portion upset from said tubular fitting subsequent to insertion thereof through the perforation in said bow.

15. A bow means operated pneumatic missile-projector, comprising: bow means, including a bow and a bow string; air compressor means, including a cylinder, and a piston operable to compress air in said cylinder; missile accommodating means; said projector having a passage for conducting the compressed air from said cylinder into said missile accommodating means to project a missile therefrom; said bow string and said bow cooperating to operate said compressor means when said bow means are released; and a barrel carried by said projector, projecting in advance of said bow, having a bore communicable with said missile accommodating means, operable to exert a directional influence upon a missile issuing therefrom, and providing an extension which may be aimed in the manner of a gun barrel; said barrel and said cylinder being of integral formation.

16. A bow means operated pneumatic missile-projector, comprising: bow means, including a bow and a bow string, said bow having a central perforation; air compressor means, including an integrally formed tubular fitting having an air compressing cylinder, missile accommodating means, and a barrel communicating with said missile accommodating means, said fitting having a passage for conducting the compressed air into said missile accommodating means to project a missile therefrom and through said barrel; and said bow string and said bow cooperating to operate said compressor means when said bow means are released, said fitting extending through the perforation in said bow, and having spaced abutment means fitting against opposite sides of said bow, one of said abutment means comprising a portion upset from said tubular fitting subsequent to insertion thereof through the perforation in said bow.

HARRY A. DOUGLAS.
